UNITED STATES PATENT OFFICE.

WILLIAM KASTENS, OF SPRINGFIELD, OHIO.

SPRING-WHEEL.

1,220,425.

Specification of Letters Patent. Patented Mar. 27, 1917.

Application filed December 26, 1916. Serial No. 133,905.

To all whom it may concern:

Be it known that I, WILLIAM KASTENS, a citizen of the United States, residing at Springfield, in the county of Clark and 5 State of Ohio, have invented certain new and useful Improvements in Spring-Wheels, of which the following is a specification, reference being had to the accompanying drawings.

10 This invention relates to certain improvements in spring wheels and it is an object of the invention to provide a device of this general character having novel and improved means whereby the jars or vibrations incident to travel are substantially absorbed.

15 It is also an object of the invention to provide a device of this general character wherein a felly is yieldably supported and 20 capable of limited movement in a circumferential direction.

25 The invention also has for an object to provide a wheel of this general character including a substantially hollow felly having coacting therewith means for effectively preventing relative movement of the side walls of said felly.

30 The invention consists in the details of construction and in the combination and arrangement of the several parts of my improved wheel whereby certain important advantages are attained and the device is rendered simpler, less expensive and otherwise more convenient and advantageous for use, 35 all as will be hereinafter more fully set forth.

The novel features of the invention will hereinafter be definitely claimed.

40 In order that my invention may be the better understood, I will now proceed to describe the same with reference to the accompanying drawings, wherein—

45 Figure 1 is a fragmentary view in elevation with portions broken away of a wheel constructed in accordance with an embodiment of my invention;

Fig. 2 is a fragmentary view in plan of the felly as herein embodied;

50 Fig. 3 is a fragmentary enlarged sectional view taken circumferentially of the wheel as herein disclosed, the coacting portion of a spoke being shown in elevation;

Fig. 4 is a sectional view taken substantially on the line 4—4 of Fig. 1;

55 Fig. 5 is a view in end elevation of a cushion-

ioning member as herein employed, the coacting holding plate being omitted;

Fig. 6 is a sectional view taken substantially on the line 6—6 of Fig. 3;

Fig. 7 is a fragmentary view partly in elevation and partly in section illustrating a slightly modified form of invention; and

Fig. 8 is a plan view of the holding plate as herein disclosed coacting with a cushioning member.

As disclosed in the accompanying drawings, H denotes a hub of any ordinary or preferred construction and having radiating therefrom the spokes S.

The outer end portion of each of the 70 spokes S is reduced, as indicated at 1, and said reduced portion is insertible within a sleeve 2. The outer end of the sleeve 2, as is particularly illustrated in Fig. 3, is provided with the tapered extension 3 adapted 75 to be accommodated with a correspondingly formed opening 4 produced in the annular member M.

The member M is positioned within the felly F and as is illustrated in Fig. 4 of the 80 accompanying drawings, it is to be noted that the felly F is substantially U-shaped in cross section. In order to facilitate the positioning of the member M within the felly F I find it of advantage to form said member M of two sections, adjacent ends being pivotally connected, as indicated at 5, while the opposite ends of said sections are adapted to be secured one to the other in any desired manner, as at 6 (Fig. 1.)

The inner or intermediate wall 7 of the felly F is provided with the circumferentially directed slots 8 through each of which is loosely disposed a sleeve 2 whereby it will be perceived that the felly F is capable of 95 movement independently of the member M.

As is clearly illustrated in Fig. 3, it is to be noted that the clamping screw 9 coacts with the outer end portion of the sleeve and member M for holding said sleeve 2 and 100 member M against relative movement so that the member M is effectively maintained, when in applied position, concentric to the axial center of the wheel or more particularly the hub H.

Opposed faces of the sleeve 2, as indicated at 10 in Fig. 6, are flattened, and slidably mounted upon the sleeve 2 is the plate 11 of a length in excess of the length of the adjacent slot 8. It will also be self-evident 110

that the flattened faces 10 of the sleeve 2 serve to hold the plate 11 against rotation about the sleeve, as the opening in the plate 11 through which the sleeve is directed is of 5 the same configuration as the cross sectional form of the sleeve 2.

Threaded upon the inner end of the sleeve 2 is the nut N of any desired type, and interposed between said nut N and the plate 11 10 is the expandable member 12 herein disclosed as a conventional coil spring encircling the sleeve 2.

The members 12 serve to maintain the 15 felly F, when the wheel is free of load, substantially concentric to, the member M or the hub H but it will at once be self-evident that the felly F is capable of yielding movement when under load independently of the member M.

20 It will also be clearly apparent that the tension of each of the members 12 may be readily varied by adjustment of the coacting nut N longitudinally of the section 2. In order to hold each of the nuts N against 25 rotation I find it of advantage to employ in connection therewith a jam nut J also in threaded engagement with the inner end portion of the member 2 and inwardly of the nut N.

30 The outer or open face of the felly F is closed by the annular rim R to which is suitably affixed the tire T of rubber or any desired material as I do not wish to be understood as limiting myself in any manner as 35 pertains to the character of the tire T. It is also to be understood that the rim R is to be considered a part of the felly F so that said felly may be defined as being hollow.

As herein embodied, the rim R is held in 40 applied position upon the felly F through the medium of the inwardly directed bolts 14 disposed through the marginal portions of the rim R and in contact with the outer face of the side portions 15 of the felly. The 45 inner end portions of the bolts 14 are disposed through the extremities of the cross bar 16 extending across and in contact with the inner face of the intermediate wall 7 of the felly F.

50 17 denotes clamping nuts threaded upon the inner extremities of the bolts 14 and arranged for contact with the bars 16 whereby it will be perceived that the rim R may be effectively held in applied position upon the 55 felly F. It is also thought to be self-evident especially in view of the disclosure in Fig. 4 that the position of the bolts 14 effectively serve to prevent outward spreading of the side portions 15 of the felly F.

60 It is essential that the side portions 15 or more particularly the opposed faces thereof be substantially parallel so that no obstruction will be afforded to the movement of the felly F relative to the member 65 M and in order to hold said side portions 15

against inward movement which would have a tendency to bind upon the member M, I interpose between the outer margins of the portions 15 the cross bars 18 provided at opposite ends with the reduced extensions 70 19 seated within suitable recesses or notches 20 produced in the outer edges of the portions 15.

It is thought to be obvious that the slots 8 25 permit limited movement in substantially a circumferential direction of the felly F which is of especial import in the event the tire should receive an unusual jolt.

C denotes a cushioning member interposed between the member M and the rim R in substantial alignment with each of the sleeves 2 or spokes S, and as herein embodied, the cushioning member C comprises a substantially rectangular compressible body 21 of rubber or the like preferably 55 with its longitudinal axis disposed circumferentially of the member M and said body 21 adjacent its longitudinal margins is provided with the outstanding compressible lugs 22 adapted to frictionally engage the 90 inner surface of the rim R, whereby the rim R is effectively maintained against circumferential movement independently of the member M and whereby the rim R and the felly F are maintained properly centered. 95

The cushioning member C may be secured to the member M in any desired manner but it is preferred that the plate P be employed to overlie the outer face of the body 21 and provided with the slots 23 through which 100 the lugs 22 extend. The plate P is also provided adjacent its opposite ends and at substantially its transverse center with the openings 24 through which the retaining screws 25 or the like are adapted to be 105 passed to anchor the body 21 to the member M.

When a wheel constructed in accordance with my invention is adapted for use in connection with unusually heavy vehicles, it is preferred that the form of invention be employed as is particularly illustrated in Fig. 7. The parts shown in this Fig. 7, which are substantially the same as set forth in the remaining figures, are identified by corresponding reference characters for convenience of identity. As disclosed in this Fig. 7, the sleeve 2 has slidably engaged therewith the plate 26 with which coat the nuts N' and J', and interposed between the ends of the plate 26 and the plate 11^a are the expandable members 27 herein disclosed as conventional coil springs for a purpose which is believed to be clearly apparent to those skilled in the art to which my invention 115 pertains.

From the foregoing description, it is thought to be obvious that a wheel constructed in accordance with my invention is 120 of an extremely simple and comparatively 130

inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I claim:

15 1. A wheel comprising a hub, spokes radiating therefrom, a substantially hollow felly provided with circumferentially disposed slots through which the outer end portions of the spokes are freely insertible and whereby said felly is capable of limited circumferential movement independently of the spokes, an annular member arranged within the felly and to which the spokes are attached, yieldable means coacting with the felly for controlling the movement thereof

longitudinally of the spokes, and compressible bodies carried by the annular member and frictionally engaging the rim.

2. A wheel comprising a hub, spokes radiating therefrom, a substantially hollow 30 felly provided with circumferentially disposed slots through which the outer end portions of the spokes are freely insertible and whereby said felly is capable of limited circumferential movement independently of 35 the spokes, an annular member arranged within the felly and to which the spokes are attached, yieldable means coacting with the felly for controlling the movement thereof longitudinally of the spokes, and compressible 40 bodies secured to the annular member and provided with lugs frictionally engaging the felly.

In testimony whereof I hereunto affix my signature in the presence of two witnesses. 45

WILLIAM KASTENS.
